UNITED STATES PATENT OFFICE.

NEWTON CRANE, OF BOSTON, MASSACHUSETTS.

ILLUMINATED FOUNTAIN.

1,255,711.

Specification of Letters Patent.

Patented Feb. 5, 1918.

Application filed December 4, 1913. Serial No. 804,786.

To all whom it may concern:

Be it known that I, NEWTON CRANE, a citizen of the United States, and resident of Boston, in the county of Suffolk and State of Massachusetts, have invented certain new and useful Improvements in Illuminated Fountains, of which the following is a specification.

The present invention relates to a new and improved fountain having means for producing varied ornamental arrangements of jets together with means for illuminating such jets with constantly changing and varying colored lights. The fountain in which I have embodied the invention which I am about to describe and claim is designed to be principally a table ornament, but the invention is not by any means thus limited and its principles are applicable to fountains of any size and designed for any purpose. This invention comprises novel feature in means for controlling the flow of water, in means for governing the illumination, and in other features hereinafter fully and specifically described and claimed.

In the accompanying drawings—

Figure 1 is a vertical sectional elevation of a fountain showing the elements of one embodiment of my invention, partly in elevation and partly in section.

Fig. 2 is a vertical central section of the emission means through which the jets of water are ejected together with the mechanism for operating the same expelling the water.

Fig. 3 is a detail horizontal sectional view on line 4—4 of Fig. 2.

Fig. 4 is a plan view of the centrifugal pump which forms a part of the particular embodiment of the invention here illustrated.

Fig. 5 is a side elevation of a fragment of the water guiding vanes and channels employed in this embodiment of the invention.

Fig. 6 is a plan view of the illuminating means.

Fig. 7 is a fragmentary detail view of the screens by which the color of the illumination is varied.

Fig. 8 is a plan view of the water ejecting means of the fountain.

Fig. 9 is an elevation of the same on a reduced scale, showing a possible arrangement of water jets which may be produced thereby.

Fig. 10 is an under plan view of a part

of the driving mechanism and the means for putting the same into and out of operation.

Fig. 11 is a similar view of said mechanism showing the same in a different position.

Fig. 12 is an elevation of the said mechanism as seen from the right of Fig. 10.

Fig. 13 is a detail under plan view on a larger scale of a part of the said mechanism.

Fig. 14 is a plan view of the same representing the opposite side from that shown in Fig. 13.

Fig. 15 is a sectional view of the same on line 16—16 of Fig. 13.

The same reference characters indicate the same parts in all the figures.

The embodiment of the invention herein illustrated, which represents the fountain designed as a table ornament, includes a casing 1 in which are contained all the operating parts of the fountain and which is adapted to hold a body of water. Said casing may be of ornamental design externally, and may be provided with feet 2, or other suitable supporting means, forming a base therefor. Said casing comprises a body or tank portion in which the water required for the operation of the fountain is contained, and a flaring lip 3, which extends far enough on all sides to catch the water which falls after being expelled from the jet orifices. The lip 3 has a central opening which communicates with the interior of the tank or water chamber to permit the falling water to flow into the latter.

A part of the bottom of the tank is elevated to form a raised platform or plate 4 attached to surrounding walls 5, said platform and walls 5 being surrounded by and submerged in the water and inclosing an open space from which the water is excluded and in which may be contained operating and driving mechanisms. Said space may be inclosed at the bottom by a cup 6, as shown in Fig. 1, or in any other way, or it may be left entirely open if desired.

The platform 4 is the support for the devices through which the water is ejected and for the pump which propels the water. It is provided with a number of separated posts 7 on which are set and to which are fastened the feet 8 on a dome 9 which has a tubular portion 10 rising from its upper end and a shoulder 11 which surrounds such tubular portion. A sleeve 12 has a rotating fit upon the tubular portion 10 and rests

at its end on the shoulder 11, such portion 10 and shoulder 11 thereby forming the guiding and supporting bearings for the sleeve. The latter is retained on such bearing 5 by a nut 13 which is screwed into the internally threaded upper end of the tubular member 10 and has a lip 14 overlying the upper end of the sleeve 12. A shoulder 15 on the nut is arranged to abut against the end of the bearing tube 10 just before the lip 14 binds against the sleeve 12 and causes the nut to retain the sleeve on its bearings without binding and without appreciable end shake.

10 The sleeve 12 carries the water ejecting means which consists of three rings 16, 17, and 18 and a cap 19. The rings are connected with the sleeve by arms, which also form water conduits, the arms 20, 20 serving thus to support the outer and lowermost ring 16, the arms 21, 21 serving the same purpose for the intermediate ring 17 and the arms 22, 22 for the ring 18. These rings are of different diameters and each is sufficiently 25 removed from the planes of the others to accommodate the supporting arms and the parts to be described through which water is admitted to such arms. The cap 19 has an internally threaded flange 23 which is 30 screwed upon the end of the sleeve 12, and it also has external shoulders 24, 25, and 26 in which are respectively located the external orifices of a corresponding number of series of water passages through which the 35 water may issue, as shown in Fig. 2. It will be seen from the same figure that all of the passages open at their inner ends to the large inner cavity or chamber formed within the cap. The upper sides of the rings 16, 17, 40 and 18 are also perforated by orifices 27 through which jets of water may issue, as clearly appears in Fig. 9. Of course it is to be understood that the herein described arrangement and character of rings and cap 45 are merely one embodiment of discharge means for the jets of water and that other arrangements and forms of means may be provided to secure various desired ornamental effects in the water discharge of the 50 fountain.

The water contained in the tank 1, which rises to a height considerably above the base of the dome 9, flows around the lower edge of the latter through a screen 28, which is 55 contained between the plate 4 and an upper plate 29 fitted into the lower part of the dome against an internal shoulder 30 therein, and rises through holes 31 in the plate near the center of the dome, into a 60 space surrounded by a substantially cylindrical wall 32 which rises from the upper side of plate 29. A pump 33 is arranged to receive the water flowing over the wall 32 and to force the same through the jet outlets 65 of the rings and cap previously de-

scribed. The form of pump for such purpose here illustrated is a centrifugal pump having outer walls 34, which are somewhat bowl-shaped, that is, which extend on smooth curves upwardly from the central 70 part of the pump to the rim thereof, a flange 35 which surrounds the wall 32 and provides a bearing for the pump, vanes or buckets 36, a cover plate 37, and a tube 38 which rises from the center of the cover 75 plate, is closed at the upper end and is mounted on a driving shaft 39. The vanes or buckets 36 are so arranged as to rotate the water contained in the pump when the latter is rotated, and impart centrifugal 80 force to the water. The cover plate is supported on the buckets and its edge terminates within the rim of the outer walls of the pump, providing an annular discharge slit 40 through which the water set in motion by the pump may escape.

Power for rotating the pump and also for driving the other movable parts of the apparatus is derived from a motor 41 which may be and preferably is an electric motor 90 contained in the inclosure formed by the parts 4, 5, and 6 previously described. In these drawings only the ring carrying the field magnets and the armature shaft 42 of the motor are shown. This armature shaft 95 is connected by a coupling 43 to the shaft 39, already described, which passes through the platform or plate 4 and is contained within a sleeve 44 surrounding the shaft and lying inside the tube 38, which connects the 100 pump with the shaft. The function of the sleeve 44 is to prevent the water, which lies in the tank to a level somewhat above the pump, from coming into contact with the shaft and leaking through the shaft bearing. It thus avoids the necessity of packing the shaft. That part of the sleeve which passes through the plate 4 is formed as a bushing having a bearing for the shaft and fitted so tightly into the plate 4 as to make 110 a water tight joint to prevent leakage of water into the motor compartment beneath. A flange 45 overlying the plate 4 surrounds that part of the tube.

The water expelled from the pump flows 115 upwardly along the inner surface of the dome 4, and between such surface and an inner shield 46. Said shield has a shape similar to the inner surface of the dome and lies symmetrically and concentrically within the same as is shown in Fig. 2. On its exterior it has guide vanes 47 (shown in Fig. 5) crossing the space between the shield and the dome and providing channels through which the water may flow. These 120 vanes are inclined and curved in such directions as to check the rotary motion of the water and to deliver the water to the space within the tubular bearing 10, under pressure and free from whirling motion. In 125 130

the walls of the tubular bearing 10 are a number of ports or sets of ports 48, 49, and 50 which are adapted to register with complementary ports or passages 51, 52, and 53, respectively, in the rotary sleeve 12 and in line with the arms which support and conduct the water to the rings 16, 17, and 18, respectively. In the nut 13 and communicating with the same water space or chamber is a passage 54 which communicates with the space inside the perforated cap 19. I prefer to have the device so arranged that the water will not spurt simultaneously from all the jet outlets but instead will come 15 intermittently. It is for that reason that the rings are provided to rotate and obtain their supply through the ports above described, which register only intermittently. For the same reason I provide a valve 55 for 20 causing an intermittent discharge of jets through the cap 19. Such valve may have any character suitable for the purpose, but the form which I have adopted for my present purpose is a plate overlying the upper 25 surface of the nut 13 and having a port 56 which is adapted to register with the offset orifice 57 of the passage 54 during a certain part of the rotation of the cap. Said valve plate has a central boss 58 which is 30 grasped by a clamp 59 having a finger 60. The cap carries a pin or equivalent device 61 arranged to engage said finger and rotate the valve as the cap rotates. A spring 62 in the boss 58 and in another socket in the 35 top of the cap, presses the valve against the nut 13 firmly enough to prevent any appreciable leakage of water. Rotation of the rings and cap to produce the intermittent discharge of water from the several sets of 40 orifices is accomplished through a gear wheel 63 fixed to the sleeve 12, a pinion 64 meshing with said gear, a shaft 65 to which said pinion is connected, a gear 66 fixed to said shaft, a worm 67 meshing with gear 66, 45 a shaft 68 to which worm 67 is fastened, a worm 69 fast on shaft 68, and a worm 70 on the pump shaft meshing with worm wheel 69. Thus the water discharge devices are 50 rotated from the high speed pump shaft at a greatly reduced speed. The shaft 65 is contained in a sleeve 71 so formed with or connected to the plate 4 as to make any leakage between itself and the plate impossible. Its function is to serve as a housing for the 55 shaft 65, which passes through the plate 4, to prevent leakage around the shaft and make it unnecessary to provide any packing for that purpose.

I prefer to make the tubular portion or 60 bearing 10 detachable from the dome 9, as by providing it with screw threads which can be readily engaged with and disengaged from a threaded opening in the upper end of the dome. It is also a part of my idea to 65 provide interchangeable tubes 10 each

adapted to be mounted in the same fountain and having various arrangements of ports 50, 51, and 52 to the end that by substituting one tube for another different effects may be secured in regard to the order or duration of time in which jets are caused to spurt from the various portions of the discharge device. 70

Means are provided for illuminating the jets, such means being preferably incandescent electric lamps 72 mounted on posts 73 within the tank portion of the casing and contained in transparent cases 74, which are so connected with specially constructed sockets 75 as to exclude water from the electrical connections and contacts. These lamps being disposed under the water discharge devices direct their rays in such fashion as to illuminate the water jets. 75

I provide for obtaining color effects by 80 interposing screens between the jets and the lamps, and I vary such effects by making such screens movable. In the present embodiment of the invention I have shown three screens 76, 77, and 78 placed one above 85 another. Such screens are composed in part of, or provided with, colored portions or segments 79, as appears from Figs. 6 and 7, the difference in color being indicated by the different characters of shading applied 90 to the segments. The screens provide wide scope for the exercise of taste and judgment in designing various color effects. Such segments may be as numerous or as large as desired and may have any desired hues. 95 I do not limit my invention in this respect to any particular details, merely providing a means by which colored screens of various hues may be provided. These screens are supported at a sufficient number of points 100 upon anti-friction rolls 80 supported rotatably on brackets 81 which rise from the walls of the tank. The rolls are formed in steps, and the surface of each step supports one of the screens. The uppermost and 105 widest screen rests on the largest step of the rolls, and the successively lower and smaller screens rest upon the successively smaller steps. The uppermost screen is rotated 110 slowly by a pin 82 or equivalent connection, which rises from it into engagement with a part of the rotating water ejecting means, and the other screws are driven by the uppermost one through the supporting rolls 115 80, which are also transmission devices. The rolls are rotated through their frictional engagement with the upper screen, and impart rotation to the other screens by their frictional engagement therewith. As the ratios 120 between the diameters of the successive steps of the rolls decrease much more rapidly than the ratios of diameters of the screens, each lower screen is driven more slowly than the screen immediately above it, and thus all 125 the screens rotate at different speeds. There 130

by the colored segments of each screen are constantly changing their positions relatively to the segments of the other screens and the color effects of the illumination are correspondingly changed, since the light rays pass through all the screens. Evidently the range of color effects which may be produced by having a sufficient number of screens, a sufficient number of varicolored segments in each screen, and a wide enough variation of tints in the colored segments, is almost infinite. It may be desired to stop the progress of these changes at times when an especially beautiful or striking effect is produced, and to permit of stopping the motion of the screens and water discharging means without stopping the pump and therefore destroying the effect altogether, I have provided a means for disconnecting the transmission mechanism through which the worm 70 on the pump shaft drives the discharging device. For this purpose the shaft 68 which carries the worm 67 and gear 69 is carried by a holder 83 which is pivoted under the platform 4 upon the shaft 65 so that it may swing about the same to bring the worm wheel 69 into and out of mesh with the worm 70. The means for thus swinging the holder and screen comprises an electromagnet 84 having an armature 85 which carries a gear segment 86 meshing with a pinion 87, which latter is connected with an eccentric 88 encircled by a strap 89 from which an arm 90 extends to the holder 83, being pivoted to the latter by a pin 91. The holder is supported and prevented from sagging down on the gear 66 by the head of a screw 92, which passes through a guide slot 93 in the holder and is threaded into the plate 4. The electromagnet is normally dead and the armature, which is pivoted on a stud 94, is normally drawn away from the magnet by a spring 95. The magnet may be energized by pressing a button located at any convenient point and arranged to bring two contact members together which are in the circuit of the magnet winding. Thereupon the armature is attracted and is moved far enough to turn the pinion 87 through a semi-rotation, the number of teeth on the segment 86 and pinion 87 and the throw of the armature may be sufficient for that purpose. The pinion is connected with a clutch member having projections 96, which are adapted to engage the abrupt ends of axially offset clutch segments 97, which latter are formed upon a ratchet 98 of which the eccentric 88, previously mentioned, is a part, as appears best from Fig. 15. By the time the armature reaches the end of its swing, the pinion has turned through a semi-rotation and one of the two teeth 99 of the ratchet has been carried past a holding pawl 100, which is held up against the periphery of

the ratchet and by a spring 101. At this time one of the two pins 102 carried by the ratchet strikes a spring abutment 103 on the segment 86, and brings the rotation of the eccentric to a stop, in the position shown in Fig. 11. When the magnet control contacts are released the armature swings back and the clutch members 96 ride up over the offset complementary clutch members 97 until they pass the raised ends thereof and fall back over the abrupt shoulders at such ends. A spring 104 bears on the pinion 87, allowing the latter to move endwise on its pivot pin 105, but compelling it to spring back after having passed over the clutch segments 87 as described. It may be assumed that the cycle of operations last described has brought the worm wheel 69 into the position shown in Fig. 11. Upon next pressing the button of the magnet circuit, the armature is again given a double swing, the eccentric is rotated through another half turn, bringing the worm wheel into mesh with the worm 70, as shown in Fig. 10, and the pinion clutch is turned back again through a half turn ready to be again operated. I prefer to provide a dash pot to prevent too sudden movements of the armature. Such dash pot may be of any suitable character and is here shown as being an air cylinder of which the piston is connected by a rod 107 with the armature 85. A stop 108 limits the movement of the armature away from the magnet. Thus it will be seen that the progress of change in the effects produced by the fountain may be instantly arrested whenever an effect occurs the enjoyment of which one wishes to prolong, by simply pressing a button or momentarily closing any other kind of a switch, and the motion may be commenced again by simply again momentarily pressing a button or closing a switch.

Fountains embodying the essential principles hereinbefore described, or any of them, may be made in all sizes, from one sufficiently small to be used as a table ornament, to those large enough for use in open air parks. In the small sizes this fountain is readily portable and can be placed anywhere desired, having no other connection with surrounding objects than the cable necessary to supply power for the motor and lights. Water connections of any kind are wholly unnecessary, since the bowl or tank portion of the fountain contains all the water used, and this water is used over and over again, being caught by the out-spreading rim as the jets fall, and being returned through the screen 28 and passages 31 to the center of the pump.

While I do not limit my invention to the use simultaneously of all the various parts of the apparatus, and I claim such parts severally as parts of my original invention,

yet all of the parts described are capable of coöperating use in combination, and they are so used in the specific embodiment of the invention here illustrated.

5. What I claim and desire to secure by Letters Patent is:

1. A fountain comprising a rotatably mounted discharge device, means for conducting water to said device, an electric motor 10 gearing between said motor and said discharge device for rotating the latter continuously through a complete revolution, and means controlled by the rotation of said device for admitting the water intermittently thereto.

2. A fountain comprising a rotatably mounted discharge device, means for conducting water to said device, driving means for rotating said device continuously through a complete revolution operating independently of the flow of water to the device, and means controlled by rotation of the discharge device for causing water to be admitted intermittently thereto.

25. 3. A fountain comprising a rotatably mounted discharge device, comprising a plurality of members or portions having distinct water emission elements, means for conducting water to said device, driving means for rotating said device continuously through a complete revolution operating independently of the flow of water to the device, and means controlled by rotation of the discharge device for causing water to be admitted intermittently and at different times respectively to the several members or portions thereof.

4. In a fountain, a rotary water discharging device, a bearing for said device which 40 is also a water container, a pump arranged to force water into said bearing, a motor for driving said pump, said motor deriving its power from means other than the energy of the water flowing to the fountain, said container and said discharge device having ports which are adapted to register in a certain position of the discharge device, and means driven by said motor for rotating said discharge device continuously through 45 a complete revolution.

5. In a fountain, a bearing having an internal passage through which water is adapted to flow, a discharge device rotatably mounted on said bearing and including a portion which extends over the end of said bearing and is provided with an outlet, the bearing having lateral ports adapted to register with water-receiving inlets in portions of said discharge device which 55 surrounds said bearing, and a valve connected with said discharge device and rotated thereby located and constructed with provisions for obstructing and opening the passage from said bearing to that portion of the discharge device which extends over the bearing.

6. A fountain comprising a tubular bearing having an end closure provided with a port, a discharge device having a portion overlying said closure and provided with outlet passages mounted rotatably on said 70 tubular bearing, mechanism for rotating said discharge device, means for supplying water to the interior of said tubular bearing, complementary ports in said bearing and discharge device adapted to register periodically and thereby to admit water intermittently to the discharge device, and a valve operated by said device for intermittently covering and uncovering the port in said end closure. 80

7. A fountain comprising a tubular bearing having an end closure, a discharge device mounted rotatably on said tubular bearing, mechanism for rotating said device continuously through a complete revolution, an 85 electric motor for driving said mechanism, means for supplying water to the interior of said tubular bearing, and complementary ports in said bearing and discharge device adapted to register periodically and thereby 90 to admit water intermittently to the discharge device, said ports being arranged in a plurality of sets or groups whereby to admit water to different parts of the discharge device at different times. 95

8. In a fountain, the combination with rotating water discharging means and illuminating means, a series of color screens having differently colored portions, so arranged that the light for the illumination passes 100 through said screens in succession, connections through which water discharging means moves one of said screens, and transmission mechanism by which the last-named screen moves the others at different rates of 105 speed, whereby continual changes in the relations of the superposed colors thereof are effected.

9. In a fountain, the combination with water discharging means, and illuminating 110 means, of a screen having a plurality of variously colored portions, means for rotating said screen, a series of successively smaller screens under the first screen, all of said screens being arranged between said discharging means and said illuminating means, and rolls having steps of different diameters supporting the several screens and forming transmission means for driving the screens at different speeds. 115

10. In a fountain, the combination with automatic driving mechanism and means for changing the ornamental effects of the fountain, with electromagnetic means for instantly interrupting the driving mechanism. 120

11. In a fountain, movable water discharging means, mechanism for moving said discharging means, a pump for delivering water to said discharging means, means controlled by movement of said discharging 130

- means for admitting water at different times intermittently to different parts thereof, and means for disconnecting said mechanism, whereby to cause the discharging means to remain stationary while water continues to flow therefrom.
12. A water discharging device for a fountain comprising a tubular bearing which is also a conduit, a series of co-axial rings having perforations and a central cap having perforations mounted to rotate on said bearing, and means for furnishing water intermittently to each of said rings and said cap.
13. In a fountain, a movable water discharge device, a motor, intermeshing gear elements, one of which is driven by said motor and the other of which drives said discharge device, a holder for one of said elements, an eccentric for moving said holder and the gear element carried thereby toward and from the complementary element, a pinion, a clutch connected with said pinion and adapted to be clutched with said eccentric, a driver meshing with said pinion, an electro-magnet, and an armature for said magnet arranged to move said driver.
14. In a fountain, a movable water discharge device, a motor, and transmission mechanism through which the motor drives the discharge device, including cooperating gear elements, a holder for one of said elements movable to carry the same into and out of mesh with the co-operating element, an eccentric for moving said holder back and forth, an electromagnet, an armature for said magnet adapted to move toward and from the same, and means including gearing and a clutch for rotating the eccentric half way on each double throw of the armature.
15. In a fountain a constantly running driver, a discharge device, mechanism including cooperating gear elements for transmitting motion from said driver to said discharge device, a holder on which one of said elements is mounted arranged to move so as to bring the same into and out of mesh with the co-operating element, an eccentric coupled to said holder and arranged so as alternately to bring said gear elements respectively into mesh and out of mesh upon each semi-rotation, a freely rotatable pinion coaxial with said eccentric, a clutch arranged to couple the pinion and eccentric together in one direction of rotation and to permit free rotation of the pinion in the opposite direction, an electromagnet, an armature therefor, means tending constantly to remove the armature from the magnet, and a toothed member carried by the armature meshing with said pinion and having a sufficient number of teeth to give approximately a semi-rotation to the pinion on each throw.
16. In a fountain, a water chamber, a dome-like casing located within said chamber having a bottom wall with an inlet near the center thereof arranged to admit water from the chamber, a centrifugal pump located to rotate in a horizontal plane within said casing having a central intake over the said inlet arranged to receive water flowing through the latter, and having an upwardly directed peripheral outlet adjacent to the walls of said casing, a boss on the casing formed exteriorly as a bearing and having interior communication with the interior of the casing, and a discharge device rotatably mounted on said boss having communication with the interior thereof.
17. In a fountain, a dome-like pump casing arranged with its axis substantially vertical and having a water inlet in its bottom, a centrifugal pump arranged to rotate about the axis of the dome in the bottom part of the latter, constructed with an upwardly directed peripheral outlet and having an inlet adjacent to its axis, a boss formed on the top of said casing approximately coaxial with said pump and formed externally as a bearing and having an open interior opening into the space within the casing, whereby the water delivered by the pump is caused to flow into said boss, and a discharge device rotatably mounted upon the bearing surface of said boss, said device and the boss having complementary ports to admit water to the device.
18. In a fountain, a centrifugal rotary pump having a central inlet, a peripheral outlet directed to discharge at one side of the plane of rotation of the pump and away from such plane, and vanes disposed between said inlet and outlet to set the water in motion when the pump is operated, a casing surrounding said pump having a hollow bearing opening into the interior of the casing, said casing being formed to guide the water delivered from the pump into the interior of said bearing, and a sprinkling or discharge device mounted rotatably on said bearing, said device and the bearing having co-operating ports for passage of water.
19. In a fountain, a sprinkling device comprising a plurality of concentric rotatably mounted rings having discharge outlets, and a perforated boss over the common center of said device, and a bearing on which said device is rotatably mounted, said bearing having ports arranged to admit water to the several rings and to said boss.
20. A sprinkling or discharge device for a fountain, comprising a hub, tubular arms extending from said hub in different planes, hollow rings mounted upon said arms and having discharge outlets in communication through the interior of the arms with the interior of the hub, and a cap or boss fixed on said hub so as to extend over one end

thereof and having passages adapted to permit flow of water from the interior of the hub, said discharge device being a rigid structure adapted to be mounted and operated as a unit.

21. A fountain comprising in combination, a water container, a pump casing in said container adapted to admit water into its bottom portion, a centrifugal pump rotatably mounted in the bottom of said casing having its periphery close to the walls thereof and formed with a peripheral outlet directed toward one side of its plane of rotation, the casing having walls converging in the direction toward which said outlet is directed, and having a tubular bearing at the converging point, whereby the casing is adapted to conduct the water discharged by the pump to the interior of said bearing, and a water-discharging device mounted upon said bearing having provisions for receiving water from the latter.

22. In a fountain, a hollow bearing having ports in its sides and having a ported end cap, means for conducting water to the interior of said bearing, a discharge device comprising a hub fitting rotatably upon said bearing and a boss covering one end of said bearing and the end cap thereof, said boss being perforated, and a hub having tubular arms and hollow rings connected with said arms and having discharge devices, said hub having ports communicating with the arms adapted to register with the ports in the sides of the bearing as the device rotates, and a valve controlling the port in said end cap and means operated by rotation of the discharge device for opening and closing said valve.

23. In a fountain, a dome like member having a tubular bearing in its upper portion, a shield arranged within said member and located to provide a space between itself and the walls of said member which communicates with the interior of said bearing, a water discharging device mounted rotatably upon said bearing and having means for receiving water from the interior thereof, and a pump located within said dome and having an approximately annular outlet arranged to discharge into the space between the dome and shield.

24. In a fountain, a bearing having a hollow interior forming a water chamber and having an outlet at the end thereof, a discharge device rotatably mounted upon said bearing, mechanism for rotating said device, said bearing having a passage arranged to admit water to the discharge device, and a valve rotatably mounted on said bearing member to cover the passage therein which leads to said outlet and having a port adapted to uncover the passage at certain inter-

vals, said valve being moved in unison with the discharge device.

25. In a fountain, an upright bearing having an internal chamber, lateral ports, and an end closure provided with a passage, a water discharge device mounted rotatably upon said bearing and including a member which extends over the end closure thereof, said device having passages adapted to register with the lateral ports of the bearing, and a valve covering the end closure and having a port adapted to open the passage therein at stated intervals, said valve being connected with and driven by the discharge device.

26. A fountain comprising in combination a tank, a motor arranged below the bottom of said tank, a shaft driven by said motor rising through said bottom, means for preventing leakage of water around said shaft through said bottom, a horizontal centrifugal pump fast to said shaft submerged in the water, having a central inlet and an upwardly directed peripheral outlet, a member surrounding said pump having rising and converging walls, a bearing rising from said member having an open interior communicating with the space within said member, whereby to receive water ejected from the pump and guided thereto by the walls of said member, and a discharge device rotatably mounted on said bearing, said bearing and discharge device having communicating means for permitting flow of water.

27. A fountain comprising in combination a tank, a motor arranged below the bottom of said tank, a shaft driven by said motor rising through said bottom, means for preventing leakage of water around said shaft through said bottom, a horizontal centrifugal pump fast to said shaft submerged in the water, having a central inlet and an upwardly directed peripheral outlet, a member surrounding said pump having rising and converging walls, a bearing rising from said member having an open interior communicating with the space within said member, whereby to receive water ejected from the pump and guided thereto by the walls of said member, a discharge device rotatably mounted on said bearing, said bearing and discharge device having communicating means for permitting flow of water, a gear fastened to said discharge device, a pinion meshing with said gear, a shaft carrying said pinion, and speed reducing gearing arranged to drive said shaft from the motor shaft.

In testimony whereof I have affixed my signature, in presence of a witness.

NEWTON CRANE.

Witness:

P. W. PEZZETTI.
